UNITED STATES PATENT OFFICE.

LOUIS W. SCHNEPP, OF HUNTINGTON BEACH, CALIFORNIA, ASSIGNOR, BY DIRECT AND MESNE ASSIGNMENTS, TO FIRST NATIONAL BANK OF ANAHEIM, TRUSTEE FOR SNAP-O-STAT COMPANY, OF ANAHEIM, CALIFORNIA, A COPARTNERSHIP.

THERMOSTATIC VALVE.

Application filed February 19, 1925. Serial No. 10,230.

My invention relates to an improved thermostatic valve that is particularly designed for automatically controlling the flow of gaseous fuel to the burner of a water heater or other similar appliance, the principal objects of my invention being to provide a thermostatic valve that is relatively simple in construction, capable of being easily and cheaply produced and which is positive and efficacious in operation.

Further objects of my invention are, to provide a thermostatic valve of the character described that is quick acting in the opening of the port or duct through which the gas passes to the burner; to provide simple and efficient means whereby the expansible member that carries the valve may be easily and accurately adjusted so as to regulate the size of the opening of the port that is controlled by the valve and, further, to support the entire valve upon a resilient arm and provide adjustable means whereby the valve housing may be adjusted toward or away from the wall of the heater with which it is associated.

With the foregoing and other objects in view, my invention consists in certain novel features of construction and arrangement of parts that will be hereinafter more fully described and claimed and illustrated in the accompanying drawing in which:

Figure 1 is an elevational view of the lower portion of a water heater and showing the same equipped with a thermostatic valve of my improved construction.

Fig. 2 is an enlarged vertical section taken on the line 2—2 of Fig. 1.

Fig. 3 is an enlarged horizontal section taken on the line 3—3 of Fig. 1.

Fig. 4 is a vertical section taken on the line 4—4 of Fig. 3.

Fig. 5 is a perspective view of a resilient strap that is mounted on the expansible member of the thermostat and which carries the gas orifice controlling valve.

Referring by numerals to the accompanying drawings, 10 designates a shallow cup-shaped housing having a removable front wall or cover plate 11 and secured to the rear lower portion of said housing is the upper end of a resilient arm 12.

When the thermostatic valve is associated with a water heater and its burner, as illustrated in Fig. 1, the lower portion of arm

12 is secured to the lower portion of the body of the tank T, so that housing 10 occupies a position immediately adjacent to the wall of the water chamber within the tank. A lug or rib 14 that projects rearwardly from the upper portion of housing 10 is adapted to bear against the wall of the tank T, to hold said housing a slight distance away from said tank.

To adjust the housing away from the tank and retain it in such adjusted position, a screw 15 passes through a lug 16 at the top of the housing with the point of said screw bearing on the tank wall.

A gaseous fuel supply pipe 18 connects with the lower end of duct 19 that is formed in the lower portion of housing 10 and which leads upwardly to a centrally arranged port 20, having an annular valve seat 21.

Leading from an outlet port 22 that is formed in the bottom of housing 10, to a gaseous fuel burner (not shown) that is arranged beneath tank T, is a pipe 23.

An adjusting screw 24 is seated in the center of cover plate 11, the outer end of said screw being slotted to receive the point of a screwdriver and said outer end of this screw is normally covered by a readily removable cap 25.

Secured to the inner end of the screw is a hollow diaphragm 26, preferably formed of thin, resilient sheet metal and which is adapted to contain a readily expansive fluid such as ether. This diaphragm is in the form of a disc and its inner wall, or that wall that is adjacent to the port 20 is preferably provided with one or more annular ribs or corrugations such as 27.

Extending entirely around the diaphragm 26 is a diametrically arranged strap 28 of thin resilient material, the inner leg or portion of which is provided with ribs or corrugations 29 that coincide with the ribs 27 on diaphragm 26.

Secured in any suitable manner to the central portion of the inner leg of strap 28 is a disc valve 30 that is adapted to rest on valve seat 21.

The inner wall of diaphragm 26 is dished inwardly, so that normally, or while the fluid within said diaphragm is not expanded, the parts are positioned so that valve 30 is maintained away from its seat, thereby

permitting gas to flow freely through which is very effective in performing its intended functions.

Formed through the lower portion of housing 10 and leading from duct 19 is a small branch duct 31, the flow of gas through which is regulated by a screw 32 and leading from said duct to the burner beneath the tank is a pilot light tube 33.

It will be understood that spring 12 tends to normally force housing 10 toward the tank T, and that by manipulation of screw 15, the proximity of the housing relative to the wall of tank T is regulated.

Obviously, when the housing is positioned immediately adjacent to the tank wall, the temperature of heated water within said tank, will cause the thermostat (the diaphragm 26) to act much more quickly than when said housing occupies a position spaced apart from said tank.

The position of the diaphragm within the housing and the degree or distance of travel of the valve 30 to and from its seat is controlled by manipulation of screw 24.

When the thermostatic diaphragm is contracted as illustrated in Figs. 2 and 3, valve 30 is unseated, so as to permit gas to flow freely from supply pipe 18 and duct 19 through open port 20 and from thence through port 22 and pipe 23 to the burner. This burner which is located immediately beneath tank T heats the water therein and when the heat reaches a predetermined degree, the fluid within diaphragm will expand, thereby forcing the dished inner wall of said diaphragm outwardly with a quick, snapping action, thereby seating valve 30 and cutting off the further flow of gaseous fuel to the burner.

Obviously, when the temperature in the tank lowers to such a degree as to cause the fluid within the diaphragm to contract and the inner wall of said diaphragm to return to its normal position, valve 30 will be unseated, thereby allowing gaseous fuel to again flow to the burner, where it will be ignited by the flame from the pilot light tube 33.

The resilient strap 28 that passes diametrically around the diaphragm, serves as a support for the valve 30, and it also cooperates with said diaphragm in producing a quick, snapping movement of said valve when it moves onto or away from its seat.

It will be noted that the diaphragm, strap and valve are all carried by the cover plate 11, and as the latter is readily removable, the inspection, repair and adjustment of the operating parts of the structure may be readily accomplished.

Thus it will be seen that I have provided a quick acting thermostatic valve that is relatively simple in structure, capable of being easily and cheaply produced, readily adjustable to suit various requirements, and

It will be understood that minor changes in the size, form and construction of the various parts of my improved thermostatic valve may be made and substituted for those herein shown and described without departing from the spirit of the invention, the scope of which is set forth in the appended claims.

I claim as my invention:

1. In a thermostatic valve, a housing having a port, an expansible fluid containing diaphragm positioned within said housing, a strap of resilient material arranged diametrically about said diaphragm, a valve carried by said strap for controlling the passage of fluid through said port and a screw projecting from the center of said diaphragm on the opposite side from the valve, which screw is seated in the wall of the housing and provides an adjustable support for said diaphragm.

2. In a thermostatic valve, a housing having a port, an expansible fluid containing diaphragm positioned within said housing, a strap of resilient material arranged diametrically about said diaphragm, a valve carried by said strap for controlling the passage of fluid through said port, a screw projecting from the center of said diaphragm on the opposite side thereof from said valve, which screw is seated in the wall of the housing and provides an adjustable support for the diaphragm, and a resilient supporting arm on which said housing is mounted.

3. In a thermostatic valve, a housing having a port, an expansible fluid containing diaphragm positioned within said housing, a strap of resilient material arranged diametrically about said diaphragm, a valve carried by said strap for controlling the passage of fluid through said port, a screw projecting from the center of said diaphragm on the opposite side thereof from said valve, which screw is seated in the wall of the housing and provides an adjustable support for the diaphragm, a resilient supporting arm on which said housing is mounted and adjustable means mounted on said housing and adapted to engage the member to which it is applied for adjusting the position of said housing away from said member.

4. In a thermostatic valve, the combination with an expansible fluid containing diaphragm, of a resilient strap disposed diametrically around said diaphragm, a valve carried by said strap and centrally arranged on one side of the diaphragm, the ends of the strap on the other side of the diaphragm being spaced apart and a screw projecting from the body of the diaphragm between the spaced ends of said strap.

In testimony whereof I affix my signature.

LOUIS W. SCHNEPP.
